UNITED STATES PATENT OFFICE.

FREDERIC A. DELANO, OF CHICAGO, ILLINOIS, ASSIGNOR TO THE NATIONAL
MALLEABLE CASTINGS COMPANY, OF CLEVELAND, OHIO.

DESIGN FOR A RAIL-BRACE FOR RAILWAYS.

SPECIFICATION forming part of Design No. 24,159, dated March 26, 1895.

Application filed February 2, 1895. Serial No. 537,125. Term of patent 14 years.

To all whom it may concern:

Be it known that I, FREDERIC A. DELANO, a citizen of the United States, residing at Chicago, Cook county, Illinois, have invented and 5 designed a new and original Design for Rail- Braces for Railroads, reference being had to the accompanying drawing, forming a part hereof.

In the accompanying drawing, the figure is 10 a perspective view of my rail brace which fully illustrates my design.

The leading feature of my design consists in a body portion provided with a raised front portion and tapering side ribs or flanges unit- 15 ing such raised front and body portion, the outlines which, when viewed in perspective as in the drawing, will present a hooded appearance and fall within a substantially cross shaped outline.

A is the body portion, somewhat resembling 20 a cross, and provided with several holes, a.

B is the brace portion, having a flattened side and rounded corners, b, substantially con- 25 vex in shape.

C are ribs which unite the brace and 25 body portions together, and c' a projecting flange at the upper portion of the brace, which unites the ribs, C, C, together—the whole pre- 30 senting to the eye a harmonious and ornate figure substantially as illustrated in the draw- ing.

I claim—

The design for a rail brace for railroads herein shown and described.

FREDERIC A. DELANO.
